CUSHIONED CARTON

Filed July 11, 1927

Inventor:
John E. Walsh,
by Mr. F. F. Friedenreich, Atty.

UNITED STATES PATENT OFFICE

JOHN E. WALSH, OF CHICAGO, ILLINOIS, ASSIGNOR TO SELF LOCKING SCHURMANN COMPANY, A CORPORATION OF ILLINOIS

CUSHIONED CARTON

Application filed July 11, 1927. Serial No. 204,710.

The ordinary egg carton, made of light cardboard, does not afford much protection to the eggs therein if the filled carton is set down heavily or struck on the bottom or the sides with sufficient force to break an egg in the event that the blow came directly upon the egg.

The object of the present invention is to provide a simple and novel expedient that will not add greatly to the cost of a carton, by means of which eggs packaged in the carton will be effectively cushioned.

The various features of novelty whereby my invention is characterized will herein after be pointed out with particularity in the claims; but, for a full understanding of my invention and of its objects and advantages, reference may be had to the following detailed description taken in connection with the accompanying drawing, wherein:

Figure 1 is a top plan view of an egg carton arranged in accordance with the present invention, open and ready to receive the eggs, only a fragment of the cover being shown; Fig. 2 is a top plan view of the opposite end of the carton, closed; Fig. 3 is a section, on a larger scale, taken approximately on line 3—3 of Fig. 1; Fig. 4 is a section taken approximately on line 4—4 of Fig. 3; and Fig. 5 is a central longitudinal section through one end of the carton.

Referring to the drawings, 1 represents the rectangular body and 2 the cover of a well known form of egg carton, namely a carton which, with the exception of the longitudinal partition, is made from a single blank. The front wall 3 of the carton is lower than the rear wall to which the cover is attached, and has connected thereto a false top whose width is equal to that of the carton and which is provided along its free long edge with an attaching strip 4 to be secured to the rear wall of the carton. The transverse partitions 5 are made by slitting the false top to produce a series of leaves joined to the attaching strip and to the front wall of the carton by triangular corner pieces 6. When the leaves are swung down at right angles to the bottom of the carton, only the triangular corner pieces remain in a horizontal plane.

It is customary to provide a central longitudinal partition interlocked with the transverse partitions formed by the leaves, for the purpose of dividing the interior of the carton into two rows of compartments. In accordance with the present invention I so construct this longitudinal partition that it provides effective cushions for the eggs. The present invention is not concerned with the details of the carton, however; the specific form of carton illustrated being fully disclosed in Patents Nos. 1,115,476 and 1,124,266 dated respectively November 3, 1914 and January 12, 1915.

The longitudinal partition, instead of being a narrow flat strip as in the aforesaid patents, may conveniently be in the form of a wide blank of cardboard or the like comprising two central panels 7 and 8, each having approximately the shape of the ordinary single partition, these panels or sections being symmetrically disposed with respect to a longitudinal center line, together with cushioning wings. As is usual in these longitudinal partition members, slots 9 are cut inwardly through those edges of the sections 7 and 8 that are the lower edges of the partition when the latter is set into the carton. These slots may be said to divide the lower marginal portion of each section into feet. The wings are in the form of extensions to the feet; each wing being of such a width as to fit readily between two adjacent transverse partitions in the carton.

The outer ends of the wings are connected together by narrow longitudinal pieces 11 which, with corresponding narrow longitudinal extensions 12 at the ends of the blank form a continuous longitudinal marginal strip along each longitudinal edge of the blank. In using the combined longitudinal partition and cushion it is folded along its longitudinal center and bent along longitudinal lines extending along the lower or outer ends of the feet, so that the wings project laterally in opposite directions from the double partition member. The device is then applied to the carton in substantially the same way as the ordinary longitudinal partition. The inner ends of the wings are carried down

to the bottom of the carton as shown in dotted lines in Fig. 3, but the outer ends cannot move down into the carton because the connecting strips 11 between consecutive wings 8 overlie the transverse partitions or the triangular corner pieces 6 and serve as stops to limit the downward swinging movements of the outer ends of the wings. The condition of the parts is now as shown in dotted lines 10 in Fig. 3 and also as shown in Fig. 1. When eggs, such as indicated at A, A in Fig. 3, are placed in the carton, they engage the wings and the latter, being flexible, conform to the contour of the eggs and become swings in 15 which the eggs are suspended above the bottom of the carton as shown in full lines in Fig. 3. It will be seen that the connecting pieces between the outer ends of the wings rest on the broad flat triangular corner pieces 15 which may be said to form parts of the transverse partitions, and therefore there is no danger that the weight of an egg will cause the connecting pieces to be cut in two as might be the case if these connecting pieces rested 20 directly on the sharp edges of the transverse partitions.

It will therefore be seen that if a carton be set down heavily, there is no danger of breaking the eggs because they rest upon spring-like supports. Furthermore, a light blow 30 that would otherwise still be sufficient to crack an egg, against the side of the carton, is absorbed by the inward yielding of the side wall, either wholly or in part, before being 35 transmitted to the egg lying inwardly from the point at which the blow is struck; and therefore the egg is protected against breakage.

It will further be seen that my improved 40 construction gives added strength to the carton, not only because of the stiff backbone that the double longitudinal partition may be said to constitute, but also because the wings may fit between the transverse partitions and 45 thus form braces for the latter.

While I have illustrated and described with particularity only a single preferred form of my invention, I do not desire to be limited to the exact structural details thus illustrated 50 and described; but intend to cover all forms and arrangements which come within the definitions of my invention constituting the appended claim.

I claim:

55 In combination, a carton having a series of transverse partitions, of a flexible sheet much wider than the carton and comprising two continuous marginal strips and connecting pieces between the strips, each connecting 60 piece being approximately as wide as the distance between two of the transverse partitions, said sheet being folded upon itself at the middle to produce a central longitudinal partition crossing the transverse partitions, 65 while said strips rest upon the upper edges

of the transverse partitions near the sides of the carton.

In testimony whereof, I sign this specification.

JOHN E. WALSH.
